CLAIM

I claim the ornamental design for a portable computer connection terminal with keyboard, as shown and described.

DESCRIPTION

FIG. 1 is a front perspective view of a portable computer connection terminal with keyboard of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is an enlarged cross-sectional view thereof taken along lines 8-8 in FIG. 2;

FIG. 9 is an enlarged cross-sectional view thereof taken along lines 9-9 in FIG. 2;

FIG. 10 is an enlarged cross-sectional view thereof taken along lines 10-10 in FIG. 2;

FIG. 11 is an enlarged cross-sectional view thereof taken along lines 11-11 in FIG. 2;

FIG. 12 is an enlarged cross-sectional view thereof taken along lines 12-12 in FIG. 2 and FIG. 6; and,

FIG. 13 is an enlarged cross-sectional view thereof taken along lines 13-13 in FIG. 2 and FIG. 6.

The broken lines in the drawings represent portions of the portable computer connection terminal with keyboard that form no part of the claimed design. Additionally, the dash-dot-dashed lines in the drawings define the boundaries of the claimed design.
